UNITED STATES PATENT OFFICE.

FELIX BROWN, OF NEW YORK, N. Y.

DESIGN FOR A HANGER.

SPECIFICATION forming part of Design No. 14,139, dated July 31, 1883.

Application filed June 11, 1883. Term of patent 7 years.

To all whom it may concern:

Be it known that I, FELIX BROWN, a citizen of the United States, residing at New York, in the county and State of New York, have invented and produced a new and original Design for Hangers, of which the following is a specification, reference being had to the accompanying drawings.

This design consists in a frame having an arched top, a straight side, and a downwardly curved bottom, each provided with a longitudinal molding on the outer edge, combined with transverse moldings at the junctions of said top with the sides of the frame.

In the accompanying drawings, Figure 1 represents a side view, and Fig. 2 a cross-section on the line xx , Fig. 1.

Similar letters indicate corresponding parts.

The letter A designates the arched top of the frame; B, the straight side thereof, and C its bottom, the latter extending in a uniform and continuous downward-curved line from the lower end of the straight side B to the lower end portion of the remaining side, D, of the frame.

The letter E denotes a longitudinal molding on the outer edge of the arched top, and E' E" similar moldings on the outer edges of the straight side and curved bottom, respectively.

At the junction of the arched top with the sides B D of the frame are transverse mold-

ings F, said top being joined to the side D by a curve, G, also having a molding. By these features I obtain a hanger possessing a neat and characteristic appearance.

In the example shown my design is applied to a post-hanger; but it can also be applied to a ceiling-hanger, in which case the part D becomes the top, B the bottom, and A C the sides, of the article.

What I claim as new, and desire to secure by Letters Patent, is—

1. The design for a hanger, consisting of the frame having the arched top A, the straight side B, the side D, the bottom C, extending in a uniform and continuous downward-curved line from side to side, and the longitudinal moldings E E' E", substantially as shown.

2. The design for a hanger, consisting of a frame having an arched top, a straight side, and a downwardly-curved bottom, provided with longitudinal moldings on the outer edges, combined with transverse moldings at the junctions of said top with the sides of the frame, as shown and described.

In testimony whereof I have hereunto set my hand and seal in the presence of two subscribing witnesses.

FELIX BROWN. [L. S.]
